UNITED STATES PATENT OFFICE.

GEORGE E. SAVAGE AND MICHAEL SEIPS, OF MERIDEN, CONNECTICUT.

DESIGN FOR A CHAFING-DISH STAND.

SPECIFICATION forming part of Design No. 35,501, dated December 31, 1901.

Application filed November 25, 1901. Serial No. 83,657. Term of patent 7 years.

To all whom it may concern:

Be it known that we, GEORGE E. SAVAGE and MICHAEL SEIPS, citizens of the United States, residing at Meriden, New Haven county, State of Connecticut, have invented and produced a new and original Design for a Chafing-Dish Stand, of which the following is a full, clear, and exact description.

Our invention relates to a new and original design for a chafing-dish stand.

The accompanying drawing illustrates in perspective a chafing-dish stand embodying our new and original design.

In the drawing, A is a ring or annulus at the upper portion of the stand. B B are curved legs extending downwardly from said ring. C is a broad ring-like plate higher at the center than it is at the sides and located between the legs and below the ring A. Bridg-

ing the gap between each leg and the adjacent outer edge of the ring-like plate C is a scroll member D.

The essential or leading feature resides in the appearance of the broad plate-ring combined with the brackets and the lower portion of the chafing-dish-stand legs.

What we claim, and desire to secure by Letters Patent, is—

The design for a chafing-dish stand substantially as herein shown and described.

Signed at Meriden, Connecticut, this 22d day of November, 1901.

GEORGE E. SAVAGE.
MICHAEL SEIPS.
